Orton:

The design for a stair-rod.

UNITED STATES PATENT OFFICE.

WILLIAM T. MERSEREAU, OF ORANGE, NEW JERSEY.

DESIGN FOR STAIR-ROD.

Specification forming part of Design No. 6,204, dated October 15, 1872.

To all whom it may concern:

Be it known that I, WILLIAM T. MERSEREAU, of Orange, Essex county, New Jersey, have originated and produced a new and original Design for a Stair-Rod, of which the following is a specification:

The nature of my design is clearly illustrated in the accompanying photographic impression, to which reference is made; and consists

in corrugating a thin strip of metal, of which the stair-rod is formed, as shown.

What I claim as new is—

The design for a stair-rod, as shown.

W. T. MERSEREAU.

In presence of—

A. SIDNEY DOANE,
WM. HASTINGS.
